UNITED STATES PATENT OFFICE

166,230

ANGLE HEAD METAL-CUTTING SHEARS

Willie M. Shoffner, Dayton, Ohio

Application May 3, 1951, Serial No. 15,048

Term of patent 14 years

(Cl. D22—5)

To all whom it may concern:

Be it known that I, Willie M. Shoffner, a citizen of the United States, residing at Dayton, in the county of Montgomery and State of Ohio, have invented a new, original, and ornamental Design for Angle Head Metal-Cutting Shears, of which the following is a specification, reference being had to the accompanying drawings, forming a part thereof, wherein:

Figure 1 is a side view of an angle head metal-cutting shears, showing my new design;

Figure 2 is a fragmentary top view, thereof;

Figure 3 is a fragmentary front view;

Figure 4 is a fragmentary bottom view;

Figure 5 is a fragmentary top view thereof as they appear in partially opened position; and

Figure 6 is a fragmentary bottom view as they appear in partially opened position.

I claim:

The ornamental design for an angle head metal-cutting shears, substantially as shown.

WILLIE M. SHOFFNER.
